(57) **CLAIM**

The ornamental design for a concealed hinge as shown and described.

DESCRIPTION

1. Concealed hinge

1.1 : Perspective

1.2 : Left

1.3 : Perspective

1.4 : Unfolded

1.5 : Unfolded

1.6 : Unfolded

1.7 : Unfolded

A concealed hinge is formed from two tubular insets with a pair of wedges attached thereto; the tubular insets are mirror-symmetrical and connected via levers; the hinge is equipped with a round locking button, situated between insets, and physically attached only to one of them; between each pair of wedges, the rectangle plate is situated and attached to the levers that are visible when the hinge is opened.
